UNITED STATES PATENT OFFICE.

WILLIAM H. WINSLOW, OF CHICAGO, ILLINOIS, ASSIGNOR TO THE STEAM POWER DEVICES COMPANY, OF CHICAGO, ILLINOIS, A CORPORATION OF ILLINOIS.

MUFFLER.

1,049,433.

Specification of Letters Patent.

Patented Jan. 7, 1913.

Application filed May 15, 1909. Serial No. 496,109.

To all whom it may concern:

Be it known that I, WILLIAM H. WINSLOW, a citizen of the United States, residing at Chicago, in the county of Cook and State 5 of Illinois, have invented a certain new and useful Improvement in Mufflers, of which the following is a full, clear, concise, and exact description, reference being had to the accompanying drawings, forming a part of 10 this specification.

My invention relates to an improved muffler construction for receiving the exhaust gases from engines, and while it is designed particularly for use with internal 15 combustion engines, it may also be effectively used in connection with steam engines for eliminating the noise due to the exhaust without placing an excessive back pressure upon the engine as is commonly the result 20 with mufflers of previous constructions.

In carrying out my invention I provide a first receptacle or chamber for receiving the gases exhausted from the engine, which gases are led from said first chamber into a second 25 chamber concentric therewith. In passing from one-chamber to the other, the gases are so directed as to receive a whirling motion in a path of practically no resistance, which path, however, has a considerable length as a 30 result of passing many times around the receiving-chamber, which is circular in cross-section. In this way, therefore, I provide a means for converting the energy contained 35 in the exhaust gases from a condition of high compression and comparatively small velocity, in which condition the gases leave the engine cylinder, to a condition of comparatively low pressure and high velocity.

By my invention I also provide a means 40 by which the high velocity gases described above are discharged into the atmosphere at a practically constant rate, as a result of which the noise usually incident to the discharge of exhaust gases from engines into 45 the atmosphere is eliminated. It is to be noted that the results described above are secured without materially retarding the flow of exhaust gases from the engine to the atmosphere, since the gases are not caused 50 to make a multiplicity of sharp turns, but are on the other hand directed in such a

manner as to move continuously in paths of comparatively low resistance.

My invention further provides for initially releasing the pressure upon the exhaust 55 gases as they enter the muffler, by providing a first or receiving member of a cross-section larger than the exhaust pipe. In this modification the means used to direct the gases into the second chamber extend somewhat 60 into the first chamber, in order to necessitate a breaking up of the exhaust gases to a certain extent before they are acted upon by the directing means. This results in equalizing the flow of gases into the second chamber, and yet as a result of the cross-section of the first chamber being larger than that 65 of the exhaust pipe no considerable resistance is exerted upon the exhaust gases.

The several drawings illustrating my invention are as follows:

Figure 1 is a side view of my muffler in its assembled condition, a portion of the side wall of the outer casing being removed to show the inside of the outer chamber; Fig. 75 2 is a vertical longitudinal section through the parts shown in Fig. 1, taken along the line 2, 2 in Fig. 3; Fig. 3 is a left-hand end view of the parts shown in Fig. 1; Fig. 4 is a transverse sectional view of the parts 80 shown in Fig. 1, taken along the line 4, 4; Fig. 5 is a view similar to Fig. 1, showing a modified form of construction for directing the gases as they pass into the second chamber; Fig. 6 is a transverse sectional view of 85 the parts shown in Fig. 5, taken along the line 6, 6; Fig. 7 is a view similar to Fig. 5, and shows a modified means for directing the gases from one chamber to the other of the muffler; Fig. 8 is a transverse sectional view 90 of the parts shown in Fig. 7, taken along the line 8, 8; Fig. 9 is a view similar to Fig. 2, showing a modified form of construction in which the first or receiving chamber is of larger cross-section than the 95 cross-section of the exhaust pipe extending from the muffler to the engine; Fig. 10 is a transverse sectional view of the parts shown in Fig. 9, taken along the line 10, 10; Fig. 11 is a view similar to Fig. 2, showing a 100 modified form of muffler construction in which the first or receiving chamber sur-

rounds the second chamber; Fig. 12 is a sectional view of the parts shown in Fig. 11, taken along the line 12, 12; Figs. 13 and 14 show a modified construction similar to Figs. 10 and 9, respectively; Fig. 15 shows partially in sectional view a throttling valve mechanism for restricting, as desired, the normal outlet opening to atmosphere from the muffler; Fig. 16 is an end view of the parts shown in Fig. 15; Fig. 17 is a view of a modified form of throttling arrangement; Fig. 18 is an end view partially in section of the parts shown in Fig. 17.

As shown in Figs. 1 to 4, inclusive, my muffler consists in a tube 1 closed at its left-hand end and adapted to be connected at its right-hand end to an exhaust pipe of practically the same internal diameter, by which the exhaust gases from the engine are directed to the pipe 1. A plurality of bent tubes 3 of small bore are threaded into the pipe 1 at intervals along its length and extend outward radially from the pipe 1 in all directions from such pipe. These tubes are all bent in the same direction at their outer ends, as indicated at 5, so as to impart to the gases passing through such tubes motion in a direction practically tangential to a circle of a diameter sufficient to just surround the tubes. The exhaust gases thus directed strike against the inner wall of the inclosing casing 7, as a result of which they have imparted thereto a whirling motion within the casing 7. The casing 7 is supported at its right-hand end by a head 9, which is held in place by a nut 11 screwed onto the pipe 1. The other end of the casing 7 is closed by a head 13 screwed on the closed end of the pipe 1. The head 13 has a plurality of small openings 14 formed therein to permit the gases discharged into the casing 7 to flow from the muffler into the atmosphere. A shield 15, which consists in a disk of somewhat smaller diameter than the bore of the casing 7, is located between the left-hand tubes 3 and the head 13 in such a way as to leave a clearance opening between the disk 15 and the head 13 of considerably larger cross-section than the cross-section of the bore of the pipe 1. The clearance opening between the disk 15 and the bore of the casing 7 is so proportioned as to be equal to or somewhat in excess of the cross-sectional area of the bore of the pipe 1. As a result of the construction described, a second chamber, adapted to receive the gases from the first chamber, consisting of a pipe 1, is formed by the casing 7 and the heads 9 and 13, and the gases directed by the tubes 3 into the second chamber are caused to move many times around the inside of the casing 7 before they finally pass along in the chamber to the outlet opening between the disk 15 and the chamber 7. As the

gas is communicated to the receiving chamber 1 it is under a comparatively high pressure and has a comparatively low velocity. The high pressure causes the gases to flow very rapidly through the tubes 3, which are provided in sufficient number so that the entire area of discharge represented by their combined openings is as great or slightly in excess of the cross-sectional area of the bore of the pipe 1. As the gases leave the pipes 3 and enter the second chamber, the pressure is at once reduced, and the directional tendency given the gases by the tubes 3 causes them to receive an extremely high velocity in a circular direction inside of the casing 7. In this way the energy represented by the high pressure is dissipated and converted into high velocity, and by the time the gases finally reach the discharge opening between the disk 15 and the casing 7, the excess of pressure upon the gases is very small. After passing the disk 15 the gases pass between such disk and the head 13 and through the openings 14 in such head into the atmosphere. A further result of the construction described is that the whirling gases within the casing 7 effectively equalize the shock of the explosion resulting from exhausting the gases from an internal combustion engine into the first chamber, and the gas issuing from the openings 14 does so with practically no impulse, but on the other hand flows out almost at uniform velocity.

The construction shown in Figs. 5 and 6 is similar to that already described in connection with Figs. 1 and 2, the difference being that the directing tubes 3 are differently disposed and that in addition to these tubes, directing vanes 16 are provided to keep the gases in a path along the inner surface of the casing 7 after they are discharged from the tubes 3. The vanes 16 effectually prevent local circulation of the exhaust gases at or near the outer surface of the pipe 1, which circulation, if it took place, would in a measure interfere with the efficient operation of the muffler.

The modification shown in Figs. 7 and 8 accomplishes the result described in connection with the modification shown in Figs. 5 and 6 wholly by the use of directing vanes 17 and 18 instead of by the use of the tubes 3. In this modification two longitudinal vanes 17 and 18 are secured to the outside of the pipe 1 in such a manner that a longitudinal series of openings 19 formed in the pipe 1 open between the vanes 17 and 18. These vanes extend outward and are curved in a direction to discharge gases passing between them from the openings 19 in a direction practically tangential to the inside of the casing 7. As a result, therefore, the gases receive the same whirling motion as already described for the other modifications and the

vanes 17 serve the same purpose as the vanes 16 shown in connection with Figs. 5 and 6.

In the modification shown in Fig. 9 the receiving chamber 1 has a bore considerably 5 larger than the bore of the exhaust pipe 20, as a result of which the gases on entering the receiving chamber expand to a considerable extent and lose some of the pressure to which they were subjected. The tubes 3 in 10 this modification project into the chamber 1 in such a manner that the gases contained within the chamber 1 upon expanding, coming into contact with the inner surface of such chamber, will not find a ready outlet, 15 but must necessarily move toward the center of the chamber 1 before they are discharged through the tubes 3. This results in breaking up to a considerable extent the impact exerted upon the exhaust gases and in there- 20 fore facilitating the uniform rate of discharge of the gases from the muffler, which is effected by the directing tubes 3 and casting 7 in the manner above described.

In the modification shown in Fig. 11 the 25 exhaust pipe 20 is connected through one head 21 of a receiving chamber 22 of considerably larger diameter than the diameter of the exhaust pipe 20. The receiving chamber 22 consists essentially of a pipe in- 30 ternally threaded at its ends and provided at its left-hand end with an internal ring 23 adapted to support a smaller pipe 24 concentric with the pipe 22. The pipe 24 is closed at its right-hand end by a plug 25, 35 which supports a pipe 26 of smaller diameter than the pipe 24. The ring 23 is set in from the left-hand end of the pipe 22 a sufficient distance so that a clearance opening is left between such ring and a head 27 used to 40 close the end of the pipe 22. The head 27 has a plurality of small openings 28 formed therethrough. The pipe 24 has secured therein a plurality of short tubes 29 of small bore, such tubes being obliquely disposed in 45 similar directions around the tube 24, imparting to the exhaust gases communicated to the receiving chamber 22 motion in a direction tangential to the bore of the pipe 24. Sufficient space is provided between the pipe 50 24 and the pipe 26, which is concentric therewith, to permit the gases passing from the tubes 29 to circulate freely around the pipe 26, which serves to maintain the motion of the gases in a circular path adjacent to 55 the inside surface of the pipe 24. As a result of the construction described in this modification the exhaust gases have imparted thereto a high velocity whirling motion in the pipe 24, and the energy represented by the high pressure and comparatively slow velocity characterizing the exhaust gases as they leave the engine is converted into high velocity and comparatively small pressure, the effect being to equalize

the flow of exhaust gases from the second 65 chamber 24 into the atmosphere through the openings 28 in the head 27.

In the construction shown in Figs. 13 and 14, the tube 1, adapted to receive the exhaust gases from the engine by means of 70 the exhaust pipe 20, is made comparatively large, and, in fact, in practice may be made of a sufficiently large diameter to form in connection with the inclosing shell 7 the circular path in which the exhaust gases are 75 caused to rotate after leaving the short bent tubes 3, which in this modification extend into the pipe 1 nearly to the center thereof. The result of this construction is that the exhaust gases delivered through the pipe 20 80 into the pipe 1 expand immediately to a much increased volume, and the escape of the gases from the tube 1 is made as difficult as possible without seriously interfering with the flow of such gases by placing the 85 openings of the outlet tubes in the central portion of the pipe 1. While in Fig. 14 the screen or restricting plate 15 is omitted, it is to be understood that this may be used or not as desired. The operation of this modi- 90 fication is similar to that already shown and described for the modifications above referred to.

As shown in Figs. 15 and 16, the end wall 13 of the outer compartment of the 95 muffler has centrally pivoted thereto a disk 30 in which openings 31, registering with the openings 14, are formed. The disk 30 has circular slots 32 formed therein, through which pass screws 33 threaded into the end 100 piece 13. The screws 33 and slots 32 perform the double function of limiting the motion of the disk 30 relatively to the end 13, and of clamping the disk 30 in any de- 105 sired position. I have found it desirable to make use of the construction just referred to for the purpose of securing the best working condition for the engine with which the muffler is to be used. For instance, an engine of comparatively large capacity and 110 working under conditions requiring a large volume of gas for each explosion would require an adjustment of the disk 30 to effect a comparatively large total outlet opening from the outer compartment of the muffler 115 shown in Fig. 15, while a smaller engine working under conditions requiring a com- paratively small quantity of gas for each explosion would have a tendency to race if the outlet opening were as large as found 120 desirable for the condition just mentioned. For the smaller engine, therefore, it is de- 125 sirable to reduce, to a slight extent, the total outlet opening, to afford a nominal back pressure for the engine to work against in order to prevent its running at too high a speed. By experiment, the amount of back pressure required for practical operation has

been found to be very small, as a result of which very little additional load is put on the engine by this character of regulation.

In the construction shown in Figs. 17 and 5 18, the cutlet openings from the outer compartment of the muffler are formed in the tube 7 instead of in the end 13. A ring 34 of such an internal diameter as to fit freely, without lost motion, upon the outer surface 10 of the tube 7, has openings 35 formed therein, which register with the openings 36 formed in the tube 7. Slots 37 are provided in the ring 34 through which pass screws 38 into the tube 7. The screws 38 serve to 15 limit the amount of motion that may be imparted to the ring 34, and serve also to clamp the ring in any desired angular position. By means of the arrangement just described, the total outlet opening from the 20 outer compartment of the muffler shown may be regulated as already explained in connection with Figs. 15 and 16.

While I have shown my invention in the particular embodiments herein described, I 25 do not, however, limit myself to these arrangements, but desire to claim broadly any equivalent modifications that may suggest themselves to those skilled in the art.

What I claim is:

30 1. In a muffler for engines, the combination of a first chamber having restricted outlet openings and adapted to receive the exhaust gases, a second chamber for receiving the gases as they pass from the first chamber, and means between the chambers for imparting a whirling motion to the gases in but one direction as they enter the second chamber.

2. In a muffler for engines, the combination 40 of two concentric cylindrical chambers, one of such chambers having restricted outlet openings and adapted to receive the exhaust gases from the engine and the other adapted to discharge the exhaust gases from the muffler, and means for directing the exhaust gases into said other chamber and for imparting to such gases a high velocity rotary motion against the inside of the outer wall of such other chamber.

50 3. In a muffler for engines, the combination of two concentric cylindrical chambers, one of such chambers having restricted outlet openings and adapted to receive the exhaust gases from the engine and the other chamber adapted to discharge the exhaust gases from the muffler, and curved deflectors extending from such first chamber into such other chamber to gradually change the direction of motion of the exhaust gases as they enter the other chamber to impart to such gases as they leave the deflectors a circular motion within the wall of such other chamber.

4. In a muffler for engines, the combina-

tion of two concentric cylindrical chambers, 65 one of such chambers having restricted outlet openings and adapted to receive the exhaust gases from the engine and the other chamber adapted to discharge the exhaust gases from the muffler, and a plurality of 70 similarly disposed curved deflectors extending from such first chamber into such other chamber to gradually change the direction of motion of the exhaust gases as they enter the other chamber to impart to such gases as 75 they leave the deflectors a circular motion within the wall of such other chamber.

5. In a muffler for engines, the combination 80 of two concentric cylindrical chambers, one of such chambers adapted to receive the exhaust gases from the engine and the other chamber adapted to discharge the exhaust gases from the muffler, and a plurality of 85 curved tubes of small bore extending from such first chamber into such other chamber to gradually change the direction of motion of the exhaust gases as they enter the other chamber to impart to such gases as they leave the tubes a circular motion within the 90 wall of such other chamber.

6. In a muffler for engines, the combination 95 of two concentric cylindrical chambers, one of such chambers adapted to receive the exhaust gases from the engine and the other chamber adapted to discharge the exhaust gases from the muffler, a plurality of curved tubes of small bore extending from such first chamber into such other chamber to gradually change the direction of motion of the exhaust gases as they enter the other chamber to impart to such gases as they leave the tubes a circular motion within the wall of such other chamber, and a disk for in part 100 closing the end of such other chamber to form an annular outlet from such other 105 chamber.

7. In a muffler for engines, the combination 110 of a first tube of large bore, a second tube of smaller bore having restricted outlet openings and disposed within the first tube, such second tube adapted to be connected with the exhaust pipe of the engine, and curved deflectors similarly disposed extending from the openings in the second tube into the first tube, such first tube provided 115 with an outlet opening to the atmosphere.

8. In a muffler for engines, the combination 120 of a first tube of large bore, a second tube of smaller bore disposed within the first tube, such second tube adapted to be connected with the exhaust pipe of the engine, and a plurality of curved pipes of small bore similarly disposed and extending into the first tube from holes through the second tube, such first tube provided with an 125 outlet opening to the atmosphere.

9. In a muffler for engines, the combination of a first tube of large bore, a second

tube of smaller bore disposed within the first tube, such second tube adapted to be connected with the exhaust pipe of the engine, and a plurality of curved pipes of 5 small bore similarly disposed and extending into the first tube from holes through the second tube, such pipes so disposed in the holes in the second tube as to project into such second tube, such first tube provided 10 with an outlet opening to the atmosphere.

10. In a muffler for engines, the combination of a first tube of large bore, a second tube of smaller bore disposed within the first tube, such second tube adapted to be connected with the exhaust pipe of the engine, curved deflectors similarly disposed extending from openings in the second tube into the first tube, and an end wall for the first tube of a diameter sufficiently smaller than 15 the bore of such first tube to form an outlet opening therefrom constituting practically a continuation of the clearance space between the deflectors and the first tube.

11. In a muffler for engines, the combination of a first tube of large bore, a second tube of smaller bore disposed within the first tube, such second tube adapted to be connected with the exhaust pipe of the engine, a plurality of curved pipes of small bore 25 similarly disposed and extending into the first tube from holes through the second tube, and an end wall for the first tube of a diameter sufficiently smaller than the bore of such first tube to form an outlet opening 30 therefrom constituting practically a continuation of the clearance space between the curved pipes and the first tube.

12. In a muffler for engines, the combination of a first tube of large bore, a second 40 tube of smaller bore disposed within the first tube, such second tube adapted to be connected with the exhaust pipe of the engine, curved deflectors similarly disposed extending from openings in the second tube 45 into the first tube, an end wall for the first tube of a diameter sufficiently smaller than the bore of such first tube to form an outlet opening therefrom constituting practically a continuation of the clearance space 50 between the deflectors and the first tube, and a compartment for receiving the gases discharged from such outlet opening, such compartment being provided with outlet openings to the atmosphere.

55. 13. In a muffler for engines, the combination of a first tube of large bore, a second tube of smaller bore disposed within the first tube, such second tube adapted to be connected with the exhaust pipe of the engine, 60 curved deflectors similarly disposed extending from openings in the second tube into the first tube, an end wall for the first tube of a diameter sufficiently smaller than the bore of such first tube to form an outlet

opening therefrom constituting practically a 65 continuation of the clearance space between the deflectors and the first tube, and a compartment in the first tube for receiving the gases discharged from such outlet opening, such compartment being provided with outlet openings to the atmosphere. 70

14. In a muffler for engines, the combination of a first tube of large bore, a second tube of smaller bore disposed within the first tube, such second tube adapted to be connected with the exhaust pipe of the engine, a plurality of curved pipes of small bore similarly disposed and extending into the first tube from holes through the second tube, an end wall for the first tube of a diameter sufficiently smaller than the bore of such first tube to form an outlet opening 75 therefrom constituting practically a continuation of the clearance space between the curved pipes and the first tube, and a compartment for receiving the gases discharged 80 from such outlet opening, such compartment having a perforated end wall.

15. In a muffler for engines, the combination of a first chamber for receiving the exhaust gases, an exhaust pipe of smaller cross-section than such chamber for delivering the gases thereto, a second chamber, directing means between the two chambers for conducting the exhaust gases from the first 90 chamber to the second chamber and for imparting a circular motion to such gases in the second chamber, and tubes extending 95 into such first chamber having curved ends extending into the second chamber. 100

16. In a muffler for engines, the combination of a first chamber for receiving the exhaust gases, a second chamber for receiving the gases as they pass from the first chamber, means between the chambers for imparting a whirling motion to the gases as they enter the second chamber, and means for adjustably restricting the size of the outlet opening from the second chamber. 105

17. In a muffler for engines, the combination of a first chamber for receiving the exhaust gases, a second chamber for receiving the gases as they pass from the first chamber, directing means between the two chambers for causing the exhaust gases contained 110 in the second chamber to prevent the ready escape from the second chamber of additional exhaust gases communicated thereto, and means for adjustably restricting the size of the outlet opening from the second chamber. 115

18. In a muffler for engines, the combination of a first chamber for receiving the exhaust gases, a second chamber for receiving the gases as they pass from the first chamber, means between the chambers for imparting a whirling motion to the gases as they enter the second chamber, such second

chamber having an outlet opening substantially parallel with the path of the moving gases thus produced in the second chamber, and means for adjustably restricting the size 5 of the outlet opening from the second chamber.

19. In a muffler for engines, the combination of a first tube of large bore, a second tube of smaller bore disposed within the 10 first tube, such second tube adapted to be connected with the exhaust pipe of the engine, curved deflectors similarly disposed extending from openings in the second tube into the first tube, such first tube provided 15 with an outlet opening to the atmosphere, a valve for adjustably restricting the size of the outlet opening from the first tube, and means for securing such valve in any desired adjustment.

20. In a muffler for engines, the combination of a first tube of large bore, a second tube of smaller bore disposed within the first tube, such second tube adapted to be connected with the exhaust pipe of the 25 engine, curved deflectors similarly disposed extending from openings in the second tube into the first tube, an end wall for the first tube of a diameter sufficiently smaller than the bore of such first tube to form an outlet opening therefrom constituting practically a continuation of the clearance space 30 between the deflectors and the first tube, a compartment for receiving the gases discharged from such outlet opening, such 35 compartment being provided with outlet openings to the atmosphere, a valve for adjustably restricting the size of the outlet opening from the first tube, and means for securing such valve in any desired adjustment.

21. In a muffler for engines, the combination of a first chamber for receiving the exhaust gases and having restricted outlet 45 openings, a second chamber adapted to receive the gases as they pass from the first chamber, and a plurality of deflecting devices between the chambers for imparting a whirling motion to the gases in the second chamber.

22. In a muffler for engines, the combination of a first cylindrical chamber for receiving the exhaust gases and having restricted outlet openings, a second cylindrical chamber substantially parallel with the 55 first chamber for receiving the exhaust gases as they pass from the first chamber, and means for imparting a whirling motion to the gases in the second chamber.

23. In a muffler for engines, the combination of a first cylindrical chamber for receiving the exhaust gases and having restricted outlet openings, a second cylindrical chamber for receiving the exhaust gases as they pass radially from the first chamber,

ber, and means between the chambers for imparting a whirling motion to the gases in the second chamber.

24. In a muffler for engines, the combination of a first chamber for receiving the exhaust gases and having restricted outlet 70 openings, a second chamber having an end outlet opening, such second chamber adapted to receive the gases as they pass from the first chamber, and deflectors extending from the first chamber into the second 75 chamber for directing the gases in a tangential direction as they escape into the second chamber.

25. In a muffler for engines, the combination of a first cylindrical chamber for receiving the exhaust gases and having restricted outlet openings, a second cylindrical chamber substantially parallel with the first chamber for receiving the exhaust gases as they pass from the first chamber, 85 and deflectors extending from the first chamber into the second chamber for directing the gases in a tangential direction as they escape into the second chamber.

26. In a muffler for engines, the combination of a first cylindrical chamber for receiving the exhaust gases and having restricted outlet openings, a second cylindrical chamber for receiving the exhaust gases 95 as they pass radially from the first chamber, and deflectors extending from the first chamber into the second chamber for directing the gases in a tangential direction as they escape into the second chamber.

27. In a muffler for engines, the combination of a first chamber for receiving the exhaust gases and having restricted outlet openings, a second chamber having an end outlet opening, such second chamber adapted to receive the gases as they pass from 105 the first chamber, and directing means between the two chambers for converting the energy contained in the compressed exhaust gases into a high tangential velocity component before the gases pass from the second chamber.

28. In a muffler for engines, the combination of a first cylindrical chamber for receiving the exhaust gases and having restricted outlet openings, a second cylindrical chamber substantially parallel with the first chamber for receiving the exhaust gases as they pass from the first chamber, and directing means between the two chambers for converting the energy contained in 115 the compressed exhaust gases into a high tangential component before the gases pass from the second chamber.

29. In a muffler for engines, the combination of a first cylindrical chamber for receiving the exhaust gases and having restricted outlet openings, a second cylindrical chamber for receiving the exhaust gases 125

as they pass radially from the first chamber, and directing means between the two chambers for converting the energy contained in the compressed exhaust gases into a high tangential velocity component before the gases pass from the second chamber.

30. In a muffler for engines, the combination of a first chamber having restricted outlet openings and adapted to receive the exhaust gases, a second chamber for receiving the gases as they pass from the first chamber, and means between the chambers

for imparting a whirling motion to the gases in but one direction as they enter the second chamber, such second chamber having an outlet opening substantially parallel with the path of the moving gases thus produced in the second chamber. 15

In witness whereof, I hereunto subscribe my name this 11th day of May A. D. 1909. 20

WILLIAM H. WINSLOW.
